Attorney.

UNITED STATES PATENT OFFICE.

HENRY C. WALKER, OF ST. LOUIS, MISSOURI.

MAGAZINE PENCIL.

1,408,551.

Specification of Letters Patent. Patented Mar. 7, 1922.

Application filed June 16, 1921. Serial No. 477,992.

To all whom it may concern:

Be it known that I, HENRY C. WALKER, a citizen of the United States, residing at St. Louis, State of Missouri, have invented certain new and useful Improvements in Magazine Pencils, of which the following is a specification.

My invention has relation to improvements in magazine pencils and consists in the novel details of construction more fully set forth in the specification and pointed out in the claims.

The object of the present invention is to provide a magazine pencil that shall consist of but few parts; one that is light in weight and durable; one that may be easily and quickly supplied with lead; and one possessing further and other advantages better apparent from a detailed description of the invention in connection with the accompanying drawings, in which—

Figure 1 is a side elevation of my improved pencil, parts being in section; Fig. 2 is an enlarged section of the lower part of the pencil; Fig. 3 is an enlarged section of the end of the pencil carrying the eraser; Fig. 4 is an enlarged cross-section on the line 4—4 of Fig. 2; and Fig. 5 is a cross-sectional detail on the line 5—5 of Fig. 2.

Referring to the drawings, 1 and 2 represent the propeller section and the magazine section respectively of the pencil, the propeller section 1 having a ferrule 3 fixed to its outer end, said ferrule projecting beyond the end of the section so as to provide a socket 4 for a rubber eraser 5. A cap 6 is adapted to fit over the eraser when the same is not in use, said cap having its side wall 7 slightly tapered on the inside so as to fit snugly over the ferrule. The inner end of the section 1 is reduced at *a* so as to receive a metallic cap 8 provided with screw threads 9. The outer surface of the cap 8 is flush with the surface of section 1, for a purpose presently to appear.

The magazine section 2 is traversed along its axis by a tube or lead-barrel 10, said tube being provided with oppositely disposed slits *s*, *s* extending inwardly a short distance from the outer end of the tube, and an annular shoulder 11 is formed on the tube at the base of the slits behind which is lodged a washer 12. A tapered tip 13 is disposed about the end of the tube 10, the outer end of the tip being crimped in at 14 and the inner end 16 being crimped behind the

washer 12. In assembling the pencil the main body of the section 2 which is preferably of wood, is passed over the tube 10 and the inner end of the tube upset at 16 thus securely binding the tip 13 between the washer 12 and section 2. The entire section is a compact unit as may be readily understood by referring to Fig. 2. The inner end of the section 2 is reduced at *b* and a threaded band 17 is fixed to the reduced end of the section.

The sections 1 and 2 are connected by an interiorly threaded cylinder 18 which is passed over the outer end of the section 1 and then screwed over the threads 9 of the cap 8 until the plain part *c* of the cylinder 18 engages the first thread on the cap, when it will be impossible to screw the cylinder further, said plain part *c* acting as a stop to prevent screwing the cylinder off the cap 8. A feed stem 19 is fixed into the inner end of the section 1, and when the section 2 is screwed into the cylinder 18 said feed stem traverses the tube 10. After the cylinder 18 is thus passed over the section 1 and the feed stem 19 is in place, a perforated disk *m* is passed over the stem 19 and placed within the cylinder 18 a sufficient distance in from the outer end to divide the cylinder into two threaded sections 18' and 18'', the former being traversed by the section 1 for feeding the lead and the latter receiving the threaded band 17 terminating section 2. The disk *m* is soldered or welded in place so as to form a permanent partition in the cylinder 18. A series of lead chambers 20 are formed in the section 2, said chambers being symmetrically disposed about the tube 10 and open at the inner end of the section, and a supply of leads 21 may be carried in these chambers. When it is desired to load the pencil the section 2 is unscrewed from the cylinder 18 and a stick of lead dropped from one of the chambers 20; said stick of lead then being inserted into the tube 10 from the inner end. The section 2 is then screwed into the cylinder and the pencil is ready for use, the leads being confined within the chambers by the disk *m*. As the lead becomes worn or broken the section 1 is screwed into the cylinder 18 so as to advance the feed stem 19 through the tube 10, thus propelling the lead forward a sufficient distance so that it may write. When the lead is exhausted the section 1 will be in abutting relation with

the disk *m*, and before a new stick of lead is inserted in the tube, the section 1 should preferably be withdrawn. In order that the lead may not fall out of the tube 10 when 5 the pencil is being used the slotted end of the tube 10 is sprung together sufficiently to grip the lead as it is pushed through this end by the feed stem 19.

From the foregoing it will be readily apparent that I have provided an extremely simple pencil that may be quickly reloaded when the lead in the barrel is exhausted.

Having described my invention, I claim:

1. A magazine pencil comprising a propeller section, a magazine section, and an 15 interiorly threaded cylinder connecting said sections, the magazine section being adapted to be detached from the cylinder, the propeller section being adapted to traverse the 20 cylinder and means on the cylinder for maintaining propeller section and cylinder in assembled relation.

2. A magazine pencil comprising a propeller section, a magazine section, and an 25 interiorly threaded cylinder connecting said sections, the magazine section being adapted to be detached from the cylinder for reloading, the propeller section being adapted to traverse the cylinder for feeding the lead, 30 and means for preventing separation of the propeller section and cylinder.

3. A magazine pencil comprising a magazine section, a propeller section, and an interiorly threaded cylinder connecting said 35 sections, said cylinder being provided with a partition disposed adjacent the inner end of the magazine section, the propeller sec-

tion being adapted to traverse the cylinder for feeding the lead, and means for maintaining the cylinder and propeller section in 40 assembled relation.

4. A magazine pencil comprising a propeller section, a magazine section, and an interiorly threaded cylinder connecting said sections, the magazine section being provided 45 with a series of lead chambers and adapted to be detached from the cylinder for reloading, the cylinder being provided with a disk adjacent to the magazine section for maintaining the lead in the lead chambers, 50 and means for preventing the propeller section from being unscrewed from the cylinder.

5. A magazine pencil comprising a propeller section, a magazine section, and an 55 interiorly threaded cylinder connecting said sections, the magazine section being provided with a series of lead chambers and adapted to be detached from the cylinder for reloading, the cylinder being provided 60 with a disk adjacent to the magazine section for maintaining the lead in the lead chambers, means for preventing the propeller section from being 65 unscrewed from the cylinder, a lead barrel disposed along the axis of the magazine section, means at the outer end of the lead barrel for gripping a stick of lead, and a feed stem secured in the propeller section and adapted to traverse the lead barrel for feeding the lead forward. 70

In testimony whereof I hereunto affix my signature.

HENRY C. WALKER.
